UNITED STATES PATENT OFFICE

2,374,161

LAMP SHADING DEVICE

Charles W. Belden, Cincinnati, Ohio, assignor to
The Kemper-Thomas Company, Cincinnati,
Ohio, a corporation of Ohio

Application November 10, 1943, Serial No. 509,720

1 Claim. (Cl. 240—108)

My invention relates to a novel light shade provided with means adjustable as a dial whereby a light pattern may be controlled within definite predetermined dimensions.

In the art there are many different types of electric light shades of different shapes and sizes calculated to control the rays of light which come from the lamp source, to a certain pattern.

It is the object of my invention to provide a lamp shade formed from telescoped cylindrical shades with a variable opening in an inner shade adapted to register with a fixed opening in an outer shade whereby a light pattern of specifically controlled dimensions may be simply and effectively determined.

The above objects and other objects to which reference will be made in the ensuing specification, I accomplish by that certain combination and arrangement of parts of which I have illustrated a preferred embodiment.

Referring to the drawing:

Figure 1 is a side elevation of my novel lamp shade showing the parts in one position.

Fig. 2 is a side elevation of the shade showing the parts in another position.

Fig. 3 is a perspective view showing a preferred construction of the inner telescoping cylindrical shaped shade.

The shade consists of an outer tubular casing 1, having arranged therein a rectangular shaped opening 2.

The electric light socket which is mounted at one end of the casing 1, may be of conventional design as illustrated at 3. A fluorescent tube 4 has terminal contacts 5 at the end adjacent the socket 3, and a bracket 6 carrying the return electric wire supports the connector 7 for the outer end of the fluorescent tube.

Within the tubular casing 1 there is a telescoping casing 8 having a knurled end 9, adapted to provide a simple means for adjusting the light pattern. The inner casing 8 has an opening 10 of irregular shape extending from a slot 11 of restricted dimensions to a widely opened part 12.

Referring to Fig. 2, it will be observed that the light pattern is controlled by the area of the space a, whereas in Fig. 1, the knurled end 9 having been rotated slightly, the light pattern is controlled by the space indicated at b.

As a bed lamp shade the advantage will be readily apparent. Where there are two occupants of a bed, one of the occupants desiring to read without disturbing the other who wishes to sleep, can so arrange the shade that only suffi-

cient light is permitted to be reflected out from the tube to illuminate the page of the book.

Another use is in the matter of controlling the amount of light to be used for illuminating a picture.

While I have illustrated only one arrangement of registering openings, which will permit the control of the light pattern, it will be obvious that different arrangements of cut-out portions in the telescoping tubes will permit various controls of the pattern of light.

The essential elements of my invention involve telescoping tubes with openings in the tubes, which by the turning of one of the tubes with respect to the other, can be brought into a desired degree of registry.

I have shown the inner tube with the larger irregular shaped opening, but it will be obvious that the inner tube with the irregular opening may be telescoped on the outside of the tube which holds the light socket, and the regular opening 2 may be formed in the tube 8 and the irregular opening 12 may be formed in the tube 1.

The dimensions of the shade may be varied in accordance with the particular type of use for which the shade is to be put. The type of fluorescent tube ordinarily in use for house lighting is one inch or more in diameter, so that for such type of tube the shade will necessarily have to have a diameter larger than that of the tube. Various types of illuminating bulbs may be used, such as the ordinary electric light bulb. With such a light bulb it will be desirable to arrange for methods of ventilation which can be easily provided by means of holes in the end pieces.

Electric light bulbs ordinarily give off heat so that while ventilation is required in connection with a shade for an electric light bulb, such ventilation is not necessary in connection with fluorescent tubes which do not heat up sufficiently to cause difficulty.

Telescoping tubes which form the shade may be made of paper, composition products or metal. I contemplate that the telescoping tubes shall have a frictional fit one within the other, but it will be obvious that the principle of operation will be the same whether the telescoping tubes have a frictional fit or not. With a knurled member at the end of one of the tubes as suggested at 9, it will be possible to determine the area of the light pattern once by trial, and for succeeding uses it will only be necessary to adjust the knurled end 9 with respect to the outer tube in the same position.

Having thus described my invention, what I

claim as new and desire to secure by Letter Patent is:

A lamp shading device comprising an outer tubular member having a slotted portion extending substantially lengthwise therein, an inner tubular member having a telescoping fit within the outer member and also having a slotted portion extending in a triangular arrangement, the base of the triangle having a length equivalent to that

of the lengthwise slot in the outer member, and the apex of the triangle located about ninety degrees around the circumference of the inner tubular member from the base, and means for producing relative rotary telescoping movement of the tubes one within the other, so that a desired light pattern from a source of light within the inner tube may be controlled.

CHARLES W. BELDEN.
